FAN CONSTRUCTION FOR SUCTION
CLEANERS AND THE LIKEElmer J. Kasper, Cleveland, Ohio, assignor to The
P. A. Geier Company, Cleveland, Ohio, a cor-
poration of Ohio

Application March 13, 1939, Serial No. 261,476

4 Claims. (Cl. 230—132)

My invention relates to fan construction for suction cleaners and the like, where it is desired to move substantial volumes of air from the intake side of the fan through the fan and to the discharge side thereof, to create a sub-atmospheric pressure or suction as great as possible on the intake side of the fan, and to consume as small an amount of power as possible.

It is a common expedient in connection with suction cleaner fan construction to locate one or more centrifugal fans within a tubular duct and to provide a circular baffle plate adjacent the discharge side of one or more of the fans, the circular periphery of the baffle plate being spaced from the inner usually cylindric surface of the 15 tubular housing.

With this arrangement of one or more fans in a tubular duct or housing with one or more circular baffle plates, the volume of air displaced, the degree of suction attained, and the power consumption required, has been not entirely satisfactory, in part, due to a swirling motion imparted to the air by the usual fan construction where a circular baffle plate is used.

When air has a swirling motion, it takes longer for a given volume to pass through a tube or other conduit of a given length, there is a greater friction loss, a less degree of suction attained, and a consequent increase of power consumption, than when the direction of movement of the air is more nearly straight.

The objects of the present improvements include the provision of an improved controlled air flow fan construction particularly adapted for suction cleaners and the like, and which minimizes swirling of the air passing therethrough by straightening the air flow, with a concurrent increase in the degree of suction attained, an increase in the amount of the air moved, and a reduction in the power consumption of the fan when in operation.

Further objects of the present improvements include the provision of a more efficient controlled air flow fan construction having a simplified arrangement of parts permitting economical manufacture and maintenance.

The foregoing and other objects are attained by the fan construction, parts, combinations, and sub-combinations, which comprise the present invention, and the nature of which is set forth in the following general statement, and preferred embodiments of which are set forth in the following description, and which are particularly and distinctly pointed out and set forth in the appended claims forming part hereof.

The nature of the improved controlled air flow fan construction of the present invention may be stated in general terms as including a conduit or duct, preferably a cylindric tubular duct, one or more preferably centrifugal fans rotatably mounted within the duct, preferably coaxially therewith, each fan having an intake side and a discharge side, and improved air flow controlling baffle means located preferably closely adjacent to the discharge side of at least one of the fans, the improved baffle means including a wall transversely extending across the opening of the duct, the outer peripheral portions of the transverse baffle wall having formed therein preferably circumferentially spaced air passages, preferably arcuate notches or openings, with radial deflecting portions between the notches or openings, the radial deflecting portions of the transverse baffle wall serving to break up and straighten out the swirling motion which is normally imparted to the air flowing through a centrifugal fan.

In some instances it is desirable to utilize at the discharge side of a fan more than one of the improved transverse baffle walls with radial deflector tongues or necks between circumferentially spaced notches or openings located relatively close to the inner surface of the tubular duct in which the fan or fans are mounted.

Also in some cases, it may be desirable, by circumferentially spaced openings in one of the improved transverse baffle walls, such openings being located relatively close to the axis of rotation of the fan, to by-pass some of the air flowing through the fan so that the by-passed air discharges relatively close to the axis of rotation, but it is normally desired to attain the greater volume of air flow closely adjacent the inner surface of the tubular duct or tubular housing means in which the fans are located and operate.

By way of example, embodiments of the improved controlled air flow fan construction of the present invention are illustrated in the accompanying drawings formed part hereof, in which

Figure 1 is a side elevation of a tank type suction cleaner, including the present improved controlled air flow fan construction, with a fragmentary showing of the suction intake tube thereof and the electric power supply line thereof, the longitudinal axis of the tank, and the general direction of air flow therethrough, being at a slight angle with the horizontal, and which for purposes of convenience of reference herein-

after may be termed a horizontal tank type suction cleaner;

Fig. 2, an enlarged fragmentary view thereof with portions broken away and shown in vertical section on the longitudinal axis of the cleaner, and other interior portions of the cleaner being shown in elevation;

Fig. 3, a fragmentary transverse sectional view thereof as on line 3-3, Fig. 2;

Fig. 4, a transverse sectional view thereof with distant parts removed as on line 4-4, Fig. 2 showing the details of one embodiment of the improved baffle means of the present invention;

Fig. 5, a fragmentary detached view illustrating in detail a second embodiment of the improved baffle means of the present invention, which in Fig. 2 is located in the discharge end of the cleaner.

Fig. 6, a side elevation of another tank type suction cleaner including other embodiments of the present improved controlled air flow fan construction, with a fragmentary showing of the suction tube and the electric power supply line thereof, the longitudinal axis of the tank or tube being vertical and the general direction of air flow through the cleaner being along the vertical axis, and which for convenience in reference will be hereinafter designated a vertical tank type suction cleaner;

Fig. 7, an enlarged fragmentary view thereof with portions in section on a vertical plane including the vertical axis of the cleaner, and other interior portions of the cleaner being shown in elevation;

Fig. 8, a fragmentary transverse horizontal section thereof illustrating in detail a third embodiment of the improved baffle means of the present invention;

Fig. 9, a transverse horizontal sectional view thereof with distant parts removed illustrating a fourth embodiment of the improved baffle means of the present invention; and

Fig. 10, a detached perspective view of the fourth embodiment of the improved baffle means.

Similar numerals refer to similar parts throughout the drawings.

In Figs. 1 to 5 inclusive there are illustrated a horizontal tank type suction cleaner indicated generally by 11, and including embodiments of the present improved controlled air flow fan construction, in addition to other improvements which are not the subject matter of the present invention, together with other usual parts of a tank type suction cleaner.

The horizontal tank type suction cleaner 11 includes as illustrated an elongated cylindric central filtering means housing tube 12 upon one end 13 of which a reducing flange cap 14 is mounted.

The larger end 15 of the reducing flange cap 14 fits over the end 13 of the central tube 12 and is separably secured thereon as by clasps 16; and the smaller outer end 17 of the reducing cap 14 separably receives a sleeve coupling 18 of a flexible suction intake tube 19.

Upon the other end 20 of the central tube 12 there is separably secured a motor driven fan unit indicated generally by 21 including embodiments of the present improvements, and the outer end of the fan unit 21 has removably secured thereon an outlet cap indicated generally by 22.

Runner rod supports 23, one for each side of the cleaner have opposite ends secured as by screws to the central tube 12 and the fan unit 21.

A carrying handle indicated generally by 24 likewise has its opposite ends secured to the central tube 12 and the fan unit 21. An electric supply flexible cable 25 is associated with a control switch indicated generally by 26 and with the preferable electric motor 27 of the fan unit 21 in an operative manner not necessary for the purposes of the present improvements to be described in detail.

The motor driven fan unit 21 including the present improved controlled air flow fan construction, includes in addition to the motor 27, other parts all located within the interior of a preferably cylindric tube 28, which as shown is part of a one piece cup having a perforated transverse wall 29 extending across the extremity of its intake end 30 telescoped within the outlet end 31 of the central tube 12. Within the central tube 12 there is located filter bag means indicated generally by 32.

The motor 27 is located within the tube 28 and includes a frame indicated generally by 33 having an apertured circular flange 34 extending transversely across the interior of the tube 28, and from opposite sides of the circular flange 34 other parts of the motor frame extend, and mount the various parts of the motor including the shaft having the fan mounting end 35 which is coaxial with the longitudinal axis 36 of the alined motor housing tube 28 and central filtering means housing tube 12.

An inner fan tube 37 has one end secured as by screws 38 to the circular flange 34 and its other end provided with a wide inwardly extending annular flange wall 39.

Longitudinally spaced from the wide annular flange 39 towards the intake perforated wall 29 there is located a circular baffle wall 40 and between the wide annular flange wall 39 and the circular baffle wall 40 there are interposed a plurality of angled deflector vanes 41. The fan tube 37 is provided with an extension fan tube 42, one end of which is telescoped as shown over the intake end of the fan tube 37 having the inwardly extending transverse annular flange 39 thereon.

The extension fan tube 42 extends over the circular baffle wall 40 and is provided at its end adjacent the perforated intake wall 29 of the outer tube 28 with a wide inwardly extending annular flange wall 43.

A preferably resilient mounting ring 45 having an L-shaped cross section is interposed between the interior circular corner of the tube 28 and the intake wall 29 and the exterior circular corner of the tube 42 and the flange wall 43.

One of the improved transverse baffle walls of the present invention indicated generally by 44 is interposed between the motor frame 33 and the inwardly extending wide annular flange 39. The fan mounting end 35 of the motor shaft extends towards the perforated intake wall 29 through central apertures of the baffle wall 44, the wide annular flange wall 39, and the baffle wall 40.

A first fan compartment 46 is formed within the extension tube 42 between the wide annular flange wall 43 and the baffle wall 40; and a second fan compartment 47 is formed within the fan tube 37 between the wide annular flange wall 39 and the improved baffle wall 44.

A centrifugal fan indicated generally by 48 is located within the first fan compartment 46, and as shown another centrifugal fan indicated generally by 48 is located within the second fan compartment 47; and the fans 48 are removably

secured to the fan mounting end 35 of the motor shaft as by cooperating nut clamped collar and spacer collar means indicated generally by 50.

Improved baffle cup means indicated generally by 51 are telescoped within the discharge extremity 52 of the outer tube 28, and as shown there may be a resilient motor support pyramid indicated generally by 53 interposed between a central pyramidal portion 54 of the cup 51 and an adjacent cylindrical end 55 of the motor frame 33.

A filter fabric wall 56 may be as shown interposed between the interior of the outlet cap 22 and the flange cup 51. The outlet cap 22 is provided with a central reduced outlet neck opening 57.

The centrifugal fans 48 as shown are identical in construction and each includes a discharge side disk 58 having a central aperture 59 fitting on the fan mounting end 35 of the motor shaft, an intake side annular disk 60 having a central intake opening 61, and preferably curved fan blades 62 interposed between the disks 58 and 60.

The intake opening 61 of the fan 48 of the first fan compartment 46, as shown, is adjacent and registers with the opening 43—1 of the wide transverse flange wall 43; and the intake opening 61 of the fan 48 in the second fan compartment 47 as shown registers with the adjacent opening 63 of the wide flange wall 39.

The improved baffle means 44 includes a transverse disk wall 64 having in its outer peripheries a plurality of notches 65, as shown arcuate notches, formed therein by radial deflector tongue portions 66 which are circumferentially spaced from each other, as are the arcuate notches 65. The radial deflector tongue portions or members 66 preferably extend to a close proximity with the inner face 67 of the tube 31.

The wall 64 has a central opening 68 fitting about a cylindric end boss 69 on the intake side end of the motor frame 21, to which the baffle wall 64 is secured as by screw means 70.

The improved baffle cup means 51, shown in Fig. 5 removed, includes a cylindric stepped flange portion 71 from the outer end of which extends inwardly a stepped baffle wall 72 having a plurality of circumferentially spaced outlet apertures 73 which as shown are arcuate in shape and are separated from each other by circumferentially spaced radial deflector spoke portions or members 74.

Between the circumferentially spaced apertures 73 and the longitudinal axis 36 passing through the center of the cup 51 there is provided a set of circumferentially spaced by-pass apertures 75 which as shown are circular in shape.

The improved baffle cup means 51 furthermore includes an outwardly extending baffle flange 76 secured upon the inner transverse stepped wall 71 and extending outwardly across and longitudinally spaced from the apertures 73. The radially extending flange 76 preferably as shown is provided at its outer periphery with a cylindric outer flange 78.

The flow of air through the suction cleaner 11 is generally in the direction of the arrows 79 parallel with the longitudinal axis 36 of the machine from the time it enters the central tube 12 from the suction tube 19, and as it passes through the perforated intake wall 29 of the fan unit 21.

The wide annular flange wall 43 of the extension fan tube 42 deflects the outer peripheral 75

portions of the incoming air through its central opening 43—1 and the central opening 61 of the centrifugal fan 48 in the first fan compartment 46, and the rapidly rotating blades 62 of the fan 48 in the first fan chamber 46 displaces the incoming air outwardly between the disks 58 and 60 towards the inner cylindric surfaces of the extension fan tube 42 which deflect the moving air about the circular periphery of the baffle wall 40 and radially inwardly towards the central opening 63 of the annular flange wall 39 where it enters the central opening 61 of the centrifugal fan 48 in the second fan compartment 47, the blades of which serve to centrifugally throw the incoming air outwardly towards the inner face of the fan tube 37 in a swirling motion which is broken up by the deflector tongues 66 which turn or deflect the air to one side or the other toward the notch portions or openings at each side of the tongues, so that the air passing through the circumferentially spaced notch portions 65 on the baffle wall 64 is straightened out to again generally take the direction of the arrows 79 in its further movement through the fan tube 37, through the apertured motor frame circular flange 34 about the motor and through the circumferentially spaced apertures 73 of the cup 51 formed by the deflector spoke portion 74 which serve to turn aside or deflect the air toward the apertures 73 and thus act as additional straightening means for the air flowing through the cleaner, part of which as it passes through the apertures 73 is deflected radially outwardly by the flange 76 and part of which preferably is by-passed through the apertures 75 of the cup means 51, serving to bag out the fabric filter wall 56, and also the by-passed air serving to cool the motor bearing located in the frame of the motor 33 adjacent the end 55 thereof.

In Figs. 6 to 10 inclusive, there are illustrated a vertical tank type suction cleaner indicated generally by 111, and including embodiments of the present improved controlled air flow fan construction, in addition to other improvements which are not the subject matter of the present invention, together with other usual parts of a tank type suction cleaner.

The vertical tank type suction cleaner 111 includes a general arrangement of parts similar to the horizontal tank type suction cleaner 11. In the vertical tank type suction cleaner 111, however, the flow of air therethrough after entering the cleaner through the suction tube 119 is vertically upwards in the general direction of the arrow 179 where the air enters the inlet opening 162 of the fan housing indicated generally by 180, and the air also emerges vertically from the outlet neck opening 157 of the fan housing 180.

The vertical tank type suction cleaner 111 includes an additional dome-shaped deflector shell indicated generally by 181, enclosing the fan housing 180.

The deflector shell 181 is provided with an upper central outlet opening 182 and a removable closure 183 which as shown is in place. The deflector shell 181 has furthermore formed therein side outlet openings 184, and when the parts of the suction cleaner 111 are in the relative positions shown in Fig. 7, after the vertically moving air discharges from the outlet neck opening 157 of the fan housing 180, it is deflected by the interior surfaces of the closure 183 and the deflector shell 181 downwardly about the exterior

of the fan housing 180 and finally laterally outwardly through the outlet openings 184.

The suction cleaner 181 includes in its fan housing 180 walls forming a first fan compartment 146 and walls forming a second fan compartment 147, there being a centrifugal fan 148 in each of the fan compartments 146 and 147, the arrangement being generally similar to that of the cleaner 11.

In the cleaner 111, however, the improved baffle means 144 at the discharge side of the first fan compartment 146 constitutes a third embodiment of the improved baffle means of the present invention; and the improved baffle means indicated generally by 244 at the discharge side of the second fan compartment 147 constitutes a fourth embodiment of the improved baffle means of the present invention.

The improved baffle means 144 as best shown in Fig. 8 includes a transverse disk wall 164 having in its outer peripheries a plurality of circumferentially spaced arcuate openings 173 which are separated from each other by circumferentially spaced spoke portions 174.

Furthermore vertically and radially arranged deflector blades 185 are located between the arcuate apertures 173 for additionally straightening out the inward radial flow of air from the openings 173.

The fourth embodiment 244 of the improved baffle means, best shown in Figs. 9 and 10 includes a cup indicated generally by 286 and having a transverse disk wall 264 and a cup flange 287 extending at right angles to the disk wall 264 from the outer periphery thereof. The disk wall 264 is provided adjacent the flange 287 with a plurality of circumferentially spaced arcuate apertures 273 which are separated from each other by circumferentially spaced spoke portions 274.

The baffle means 244 further includes angle deflector bars 288 which are radially arranged at opposite sides of pairs of the arcuate apertures 273, and each of which has a deflector blade 289 at right angles to the baffle wall 264 and extending radially from the flange 287 for straightening out and controlling the radial flow of air from the apertures 273 towards the vertical axis of the cleaner 111.

Each of the tank type suction cleaners 11 and 111 operate at a relatively high suction.

In each cleaner the use of the improved baffle means 44, 144 or 244 at the discharge side of the second fan 48 and of both fans 148, rather than the usual circular baffle walls such as the wall 40 for the first fan 48 of the cleaner 11, produces the entirely unexpected results of increasing the degree of suction attained, increasing the volume of air moved, and reducing the power consumption.

If for example in the suction cleaner 11, the improved baffle means 44 including the wall 64 with the circumferentially spaced arcuate notches 65 therein and the deflector tongues 66 are not utilized, and only a circular baffle wall is used in the position of the improved baffle wall 64, then a suction of about 38" of water may be attained with the usual 110 volt suction cleaner fan motor.

Utilizing the improved baffle means increases the suction from 1 to 2 inches of water, the maximum increase being attained when each of a plurality of fans such as the two fans 148 in the cleaner 111 are provided at their discharge side

with the improved baffle means 144 and 244 in which the radial deflector spokes 174 and 274 function in a manner similar to the deflector tongue portions 66 of the wall 64 of the cleaner 11.

In utilizing the present improved controlled air flow fan construction, suction has been increased substantially 5%, the volume of air moved has been increased about 4%, and with a reduction in the power consumption of about 4%, which results are entirely unexpected.

The embodiments of the present improvements illustrated and described herein are by way of example, and the scope of the present invention is not limited to the same or to the particular details thereof, but is commensurate with the subject matter of the following claims, the elements of any of such claims being intended to include their reasonable equivalents.

I claim:

1. Controlled air flow fan construction for suction cleaners and the like, including walls forming a duct, a motor mounted within the duct and having a shaft, a fan mounted on the motor shaft within the duct and adjacent to said motor, the fan having an intake side and a discharge side, and baffle means at the discharge side of the fan, the baffle means including a wall between the motor and the fan extending transversely across the duct and having a plurality of circumferentially spaced transverse deflecting portions forming a plurality of circumferentially spaced air passages adjacent the duct.

2. Controlled air flow fan construction for suction cleaners and the like, including walls forming a duct, a motor mounted within the duct and having a shaft, a fan mounted on the motor shaft within the duct and adjacent to said motor, the fan having an intake side and a discharge side, and baffle means at the discharge side of the fan, the baffle means including a wall between the motor and the fan extending transversely across the duct and having a plurality of circumferentially spaced transverse tongues forming a plurality of circumferentially spaced air passage arcuate notches in the wall adjacent the duct.

3. Controlled air flow fan construction for suction cleaners and the like, including walls forming a duct, a motor mounted within the duct and having a shaft, a centrifugal fan mounted on the motor shaft within the duct, the fan having an intake side and a discharge side, and baffle means at the discharge side of the fan, the baffle means including a wall extending transversely across the duct adjacent to said motor and having a plurality of circumferentially spaced transverse deflecting portions forming a plurality of circumferentially spaced air passages adjacent the duct.

4. Controlled air flow fan construction for suction cleaners and the like, including walls forming a duct, a series of fans operatively mounted within the duct, each fan having an intake side and a discharge side, baffle means at the discharge side of each fan, each baffle means including a wall extending transversely across the duct and having a plurality of circumferentially spaced transverse deflecting portions forming a plurality of circumferentially spaced air passages adjacent the duct, and a motor driving said fans mounted within the duct closely adjacent to the discharge side of the baffle means at the discharge end of said series of fans.

ELMER J. KASPER.
